PLOW DISK MOUNTING

Abel G. Harris, Tonica, Ill.

Application February 13, 1939, Serial No. 256,190

5 Claims. (Cl. 97—217)

The present invention relates to disk plows and more particularly to a novel means of mounting the same on a plow beam.

An important object of the invention resides in the provision of a plow disk mounting which permits ready adjustment of the plow disk with a minimum amount of time and effort.

Another object of the invention is the provision of a novel housing having a transverse bore therethrough for receiving a shaft adapted to support the plow disk. A bracket supported on a vertical shaft extending from the plow beam is attached to one side of the housing and includes a facing having a serrated portion engaging a corresponding serrated portion on the side wall of said housing, the plow disk being readily adjusted through the medium of the serrated portion and bracket.

A further object of the invention is the provision of a mounting having the above mentioned characteristics which will be relatively simple and inexpensive in manufacture and installation, highly efficient in use, durable in service and a general improvement in the art.

The invention will be fully and comprehensively understood from a consideration of the following detailed description when read in connection with the accompanying drawing which forms a part of the application.

In the drawing:

Figure 1 is an elevational view of a plow disk mounted in accordance with the teachings of the present invention.

Figure 2 is a vertical sectional view taken substantially on line 2—2 of Figure 1.

Figure 3 is a top plan view thereof.

Figure 4 is a sectional view taken substantially on line 4—4 of Figure 1.

Figure 5 is a sectional view taken substantially on line 5—5 of Figure 3.

Figure 6 is a front elevational view of the bracket detached from the supporting housing, and

Figure 7 is a side elevational view of the housing detached from the other parts of the mounting.

Referring to the drawing for a more detailed description thereof the plow mounting generally indicated at 10 in the several views is supported on a vertical shaft 11 extending from the plow beam, not shown, and attached thereto by any desired means. The mounting 10 includes a substantially rectangular shaped housing 12 having a central bore 13 extending therethrough for receiving an axle or shaft 14, the bore being en-

larged adjacent one end 15 thereof for receiving a roller bearing 16 and enlarged to a lesser degree on the other end 17 for receiving a relatively smaller roller bearing 18. The housing 12 is formed with an externally threaded extension 6 or boss 19, concentric with the bore 13 and adapted to receive a screw cap 20.

The axle 14 secured within the bore 13 and suitably supported on the bearings 16 and 18, respectively, is reduced and threaded at each end 10 as shown in Figure 2 of the drawing. A felt retaining washer 21 is positioned adjacent the enlarged bearing 16 and the plow disk 22 is then supported on the shaft between the washers 23 and 24, respectively, and held thereon by means 15 of the lock nut 25. The smaller bearing 18 is retained in place by means of the nut and cotter pin 26. Thus it will be seen that provision is made for the shaft 14 and disk 22 to freely rotate within the housing 12, lubricant being supplied to the rotating parts through the fitting 27.

Referring to Figure 7 of the drawing, it will be noted that the upper edge of one side wall of the housing 12 is provided with an arcuate-shaped serrated portion 28 for engagement with a similar serrated portion 29 formed on the bracket generally indicated at 30, the bracket and housing being adjustably held by means of the pair of transverse bolts 31. Loosening the bolts 31 permits adjustment of the bracket 30 through 30 the medium of the respective serrated portions 28 and 29 to change the angularity of the disk 22.

The bracket 30 is provided with a pair of spaced lateral apertured extensions 32 and 33, respectively, for receiving therebetween a collar 34 35 which surrounds the shaft 11 for attaching the bracket and housing to said shaft and to permit vertical adjustment of the disk. Set screws 35 are provided in the collar 34 for securing the bracket 30 at any desired height on the shaft. A 40 laterally extending supporting stub 36 extends from the bracket 30 and between the lateral extensions 32 and 33 for providing additional support for the bracket, the end of the stub contacting the shaft through an opening in the collar being concaved for adapting itself to the contour of the shaft.

Referring particularly to Figure 4 of the drawing, it will be noted that the portion of the bracket through which the shaft 11 extends is 50 disposed at an angle to the housing which permits properly positioning the disk plow relative to the plow beam and vertical shaft 11.

It is readily understood that lateral adjustment of the plow disk 22 is obtained through 55

the medium of the serrated portions 28 and 29 formed on the housing 12 and bracket 30, respectively. Vertical adjustment is obtained through the medium of the collar 34 and laterally extending sections 32 and 33 respectively through which the shaft 11 extends. Thus there is provided a plow disk mounting comprising a minimum number of parts that provides for proper support of the plow disk with respect to the plow beam and at the same time permitting the required adjustments necessitated in the use of such implements.

Also it will be understood, of course, by those skilled in the art that variations in the hereinabove described device involving the substitution of substantial equivalents for the devices described are intended to be comprehended within the spirit of the present invention and that the invention is capable of extended application and is not confined to the exact showing of the drawing nor to the precise construction described, and therefore, such changes and modifications may be made therein as do not affect the spirit of the invention nor exceed the scope thereof as expressed in the appended claims.

What is claimed is:

1. A plow disk mounting comprising, a shaft depending from a plow beam, a housing having a central bore extending therethrough, an axle supported within the bore of said housing and supporting on one end thereof a plow disk, means for attaching said housing to said shaft, said means including a bracket having a pair of spaced lateral apertured extensions for receiving therebetween a collar surrounding said shaft, means for permitting vertical adjustment of said collar and extensions on said shaft, and means for permitting lateral adjustment of said housing.
2. A plow disk mounting comprising, a shaft depending from a plow beam, a housing having a central bore extending therethrough, said bore being enlarged adjacent one end for receiving a roller bearing and enlarged to a lesser degree on the other end for receiving a relatively smaller roller bearing, an axle supported within the bore of said housing and in contact with said roller bearings, one end of said axle carrying a

plow disk, means on the other end of said axle for locking the same to said housing, means for attaching said housing to said shaft, said means including a bracket having spaced lateral extensions for supporting therebetween a collar surrounding said shaft, and means on one face of said bracket for permitting lateral adjustment of said housing.

3. A plow disk mounting comprising, a shaft extending from a plow beam, a housing having a central bore extending therethrough, an axle supported within the bore of said housing, means for mounting a plow disk on said shaft, means for adjustably attaching said housing to said shaft, said means including a bracket having an arcuate serrated portion engageable with a similar serrated portion on a side wall of said housing, and spaced arms extending laterally of said bracket for receiving therebetween a collar supported on said shaft, whereby said bracket and housing are vertically adjustable on said shaft.

4. A plow disk mounting comprising, a shaft extending from a plow beam, a housing and means for adjustably mounting the same on said shaft, an axle supported within said housing and having a plow disk mounted on one end thereof, and means forming a part of said housing cooperating with said housing mounting means for permitting lateral adjustment of said housing and said plow disk extending therefrom.

5. A plow disk mounting comprising, a shaft extending from a plow beam, a housing having a central bore extending therethrough, an axle supported within the bore of said housing and projecting beyond each end thereof for mounting a plow disk on one end of said axle, means for adjustably attaching said housing to said shaft, said means including a bracket having an arcuate serrated portion on one face thereof and spaced arms extending laterally from the opposed face thereof, a collar mounted on said shaft and supported between said spaced arms, said collar being movable on said shaft when adjusting the position of said housing, and means on a side wall of said housing cooperating with the serrated portion of said bracket for permitting lateral adjustment of said housing.

ABEL G. HARRIS.
